UNITED STATES PATENT OFFICE.

GERHARDT M. FALCK, OF MORRISON, WISCONSIN.

SAFETY-RECEPACLE.

1,243,498.

Specification of Letters Patent. Patented Oct. 16, 1917.

Application filed November 8, 1916. Serial No. 130,196.

To all whom it may concern:

Be it known that I, GERHARDT M. FALCK, a citizen of the United States, residing at Morrison, in the county of Brown and State 5 of Wisconsin, have invented certain new and useful Improvements in Safety-Receptacles, of which the following is a specification.

This invention relates to a safety receptacle and more particularly to a container adapted to be mounted in a convenient place on the exterior of a dwelling for receiving bottles of milk when the same is delivered and also holding empty milk bottles, the receptacle being provided with means for preventing theft of either the bottles of milk or the empty bottles after they are placed within the receptacle.

One of the objects of the invention is the provision of a receptacle having superposed compartments, one being for the reception of bottles of milk, while the other is adapted to contain the empty bottles, the compartment being arranged so that the locking mechanism therein will lock the closures for the compartment either independently of or simultaneously with each other.

Another one of the objects of the invention is the provision of two compartments, 20 the uppermost of which is provided with a drawer having a loose bottom resiliently mounted and associated with a locking mechanism disposed within the lower compartment so that when the full bottles are placed within the drawer the locking mechanism will be released for permitting the extraction of the empty bottles from the lowermost compartment.

A further object of this invention is the provision of a safety receptacle which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, where- 50 in is illustrated the preferred form of my invention, in which:

Figure 1 is a front elevation.

Fig. 2 is a vertical longitudinal section.

Fig. 3 is an enlarged detail section of a 55 fragmentary portion of the device showing the locking mechanism in operative position.

Referring to the drawing, wherein is illustrated the preferred form of my invention, and in which like numerals of reference indicate corresponding parts throughout the several views, the receptacle 1 is of substantially rectangular configuration and is provided with two interior compartments 2 and 3, the compartment 3 comprising the upper half of the receptacle and is adapted 60 to receive a drawer 4 having a knob 5 on its front so that the drawer may be withdrawn from the compartment 3 for permitting the same to be opened whereby the full milk bottles may be placed within the drawer. A central horizontal partition 6 divides the receptacle for providing the two compartments 2 and 3 and the partition is provided with a longitudinal slot 7.

The bottom wall of the drawer 4 is also 75 provided with a slot 7' in alignment with the slot 7 in the partition 6. Hingedly mounted at the bottom of the rear wall of the drawer is a plate 8. The hinges 9 connect the plate 8 with the rear wall of the 80 drawer. Secured to the bottom of the plate 8 and extending at an angle therefrom is an operating finger 8' which has its end projected into the slots 7 and 7' as clearly shown by Fig. 3 of the drawing.

A flat spring 10 is provided at one end with a flange 11 having apertures for receiving fastening bolts or rivets whereby the flange may be fastened to the rear wall of the compartment 2 at a point directly below 90 the partition. The flat spring 10 extends completely across the bottom of the partition 6.

The forward end of the spring 10 is projected upwardly at an angle to have a portion extended into the slot 7 and the end of the spring is bent downwardly from the angular portion so that its terminal is projected downwardly into the compartment 2. This depending portion provides a vertical 100 movable clip 12 having an elongated slot 13 for receiving one end of a latch 15 the opposite end of which is secured to the front door or closure 16 of the bottom compartment 2. The closure 16 is hingedly mounted by the 105 hinges 17 and is provided with a knob 18 which may be grasped for pulling the closure 16 to open position.

The top 19 of the receptacle is hingedly mounted and the rear wall thereof thus providing a top closure for the upper compartment 3 and for permitting the extrac-

tion of the bottles of milk from the drawer 4 when the same is locked within the compartment. For locking the closure 19, a rod 20 is extended transversely across the top 5 of the closure and has one end bent downwardly and then extended rearwardly for providing a rotatable staple 21 adapted to register with an eye 22 when in locked position. The opposite end of the rod 20 ex- 10 tends over the opposite edge of the closure 19 and has an aperture formed in its terminal which registers with an aperture in a lug 23 whereby the shackle of a padlock 24 may be inserted through the openings in the 15 end of the rod and in the lug 23 for locking the closure 19 in closed position.

In use, the customer will, upon retiring for the night, place the empty milk bottles in the lowermost compartment 2 and will 20 close the door 16 thus causing the latch 15 to register with the clip 12 for locking the door 16 and insuring the bottles against theft. The top closure 19 will be locked and the person delivering the milk will be 25 obliged to withdraw the drawer 4 for placing the milk bottles in the same. When the full bottles of milk are placed within the container or drawer, the plate 8 will be depressed thereby extending the finger 8' 30 through the slot 7 and exerting a downward pressure on the angular portion of the spring 10 directly above the clip 12. The door may then be opened for permitting the extraction of the empty milk bottles from the lower- 35 most compartment. The position of the finger 8', however, behind the edge of the slot 7 will prevent the drawer 4 from being withdrawn thus insuring the full bottles in the drawer against theft. The customer, 40 who holds the key to the padlock may extract the bottles of milk by unlocking the closure 19. Immediately upon removal of the full bottles of milk, the plate 8 will be forced upwardly by the spring 10 thereby 45 placing the device in position for receiving a new supply and locking the same against theft.

From the foregoing it will be observed that a very simple and durable safety receptacle has been provided, the details of 50 which embody the preferred form. I desire it to be understood however, that slight changes in the minor details of construction may be made without departing from the 55 spirit of the invention or the scope of the claims hereunto appended.

I claim:

1. A safety receptacle divided into upper and lower compartments, the upper compartment being provided with a removable 60 drawer having an opening in its bottom, a plate hingedly mounted and overlying the bottom of the drawer, the said plate carrying an operating finger extended into the 65 opening in the bottom of the drawer, a clo-

sure for the lower compartment and means mounted in the lower compartment and associated with the said closure to be operated by the said finger for releasing the said closure when a weight is applied to the said 70 plate within the drawer.

2. A safety receptacle divided into upper and lower compartments, the upper compartment being provided with a removable drawer having an opening in its bottom, a 75 plate hingedly mounted and overlying the bottom of the drawer, the said plate carrying an operating finger extended into the opening in the bottom of the drawer, a closure for the lower compartment and means 80 mounted in the lower compartment and associated with the said closure to be operated by the said finger for releasing the said closure when a weight is applied to the said plate within the drawer, a partition divid- 85 ing the said upper and lower compartments and provided with an opening in alinement with the opening in the drawer when the latter is closed, the said finger being project- 90 ed through the opening in the partition when the said plate is pressed downwardly by a weight.

3. A safety receptacle having a central partition arranged therein for providing superposed compartments, the said partition 95 having a slot communicating with the up- permost compartment, a drawer arranged within the uppermost compartment and hav- 100 ing a slot in its bottom normally in regis- tration with the slot in the said partition, and automatically operated means mounted in each of the said compartments and adapted for coöperation through the said slots where- 105 by unlocking of the closure of the lower- most compartment may be accomplished by a pressure applied from the uppermost compartment.

4. A safety receptacle having a central partition arranged therein for providing su- 110 perposed compartments, the said partition having a slot communicating with the up- permost compartment, a drawer arranged within the uppermost compartment and hav- 115 ing a slot in its bottom normally in regis- tration with the slot in the said partition, and automatically operated means mounted in each of the said compartments and adapt- 120 ed for coöperation through the said slots where- by unlocking of the closure of the lower- most compartment may be accom- plished by a pressure applied from the up- permost compartment, the same means being adapted to prevent the withdrawal of the 125 said drawer when the said pressure is applied.

5. A safety receptacle having a central partition arranged therein for providing su- 130 perposed compartments, a drawer arranged within the uppermost compartment, the bot- tom of the said drawer and the partition

each being provided with a slot adapted for registration, a plate hingedly mounted on the bottom of the drawer and projecting over the said slot in the bottom thereof, a 5 spring disposed within the said lowermost compartment and projecting into the said slot in the partition, and means carried by the said plate and adapted to engage the said spring for depressing the same within the 10 lowermost compartment when a pressure is applied to the plate.

6. A safety receptacle having a central partition arranged therein for providing superposed compartments, a drawer arranged 15 within the uppermost compartment, the bottom of the said drawer and the partition each being provided with a slot adapted for registration, a plate hingedly mounted on

the bottom of the drawer and projecting over the said slot in the bottom thereof, a 20 spring disposed within the said lowermost compartment and projecting into the said slot in the partition, means carried by the said plate and adapted to engage the said spring for depressing the same within the 25 lowermost compartment when a pressure is applied to the plate, and a clip adapted to coöperate with the said spring when the spring is in normal position.

In testimony whereof I affix my signature 30 in presence of two witnesses.

GERHARDT M. FALCK.
